TUNABLE MAGNETRON TUBE

Franzo H. Crawford, Williamstown, Mass., assignor to the United States of America as represented by the Secretary of War

Application January 3, 1946, Serial No. 638,895

2 Claims. (Cl. 315—40)

1

This invention relates generally to ultra-high frequency oscillator tubes. More particularly it relates to an improvement in tunable magnetrons for suppressing spurious resonances and maintaining a relatively more uniform "Q" of the tube.

In the development of oscillators that generate ultra-high frequencies, numerous problems have existed. Some of the most important problems have been related to spurious oscillations in tunable magnetrons. It is most desirable to solve these problems so that advantage can be taken of the well known efficiency of this type of tube. Spurious resonances are due in part to the addition of elements comprising tuning means. These means, being metallic elements fitted into the resonant cavities of the magnetrons and being relatively complex, offer conductive paths to radio frequency currents which often are long enough with respect to certain wave lengths to become resonant at corresponding spurious frequencies. The reasons for changes in "Q" is that withdrawal of the loading slug usually employed to vary self-inductance of the cavities and thus effect the frequency of oscillation lessens losses within the tube and raises the "Q" while the simultaneous insertion of metallic elements used to increase the capacity of the cavities does not add losses to a commensurate extent.

It is an object of this invention therefore to provide a magnetron tube having the advantages of efficiency and of usefulness which are generally associated with tunable magnetrons, while at the same time it will be less subject to undesired resonances and to wide variations of the "Q" of the tube.

Generally this invention comprises a magnetron either of the type known to the art as a plural cavity magnetron or of the type known as a vane type magnetron, combined with associated elements which can be controllably introduced into the electric and magnetic fields of the resonant cavities so as to increase or decrease simultaneously the capacitance and the inductance of the resonant cavities thereby altering the L—C product and the frequency of oscillation. Said associated means are composed of such materials and arranged in such a way that spurious resonances are lessened and changes in "Q" over the frequency range of tunability is reduced.

Other objects, features and advantages of this invention will suggest themselves to those skilled in the art and will become apparent from the following description of the invention taken in

2

connection with the accompanying drawing, in which:

Fig. 1 is a sectional view of a magnetron embodying the principles of this invention, said sectional view being taken along the diameter indicated by the line 1—1 of Fig. 2;

Fig. 2 is a sectional view of the same embodiment as shown in Fig. 1, this section being in a plane parallel to the ends of the cylindrical body of the magnetron and at the location shown by line 2—2 in Fig. 1;

Fig. 3 is a sectional view of a vane type magnetron having conventional tuning means, said sectional view corresponding in location to the sectional view of Fig. 2; and

Fig. 4 is a sectional view of an embodiment of this invention as applied to a vane type magnetron and therefore comprising an improvement over the magnetron shown in Fig. 3.

Referring now more particularly to Fig. 1, case 10 is the main body portion of this embodiment of this invention. Approximately midway between its ends 11 and 12, is a metallic mass 13 which is formed to contain multiple resonant cavities 14 and to contain a center cavity 15 comprising the inter-electrode space through which electrons travel from cathode 16 toward cavities 14. The location of cathode 16 is conventional, as are the design and arrangement of its heater 17. If no other parts were to be added to the structure thus far referred to, this device in the presence of the proper magnetic field and with proper heating and polarizing voltages, would be a fixed frequency magnetron oscillator. The parts to be described hereinafter are parts adapted to make it tunable, and include the novel features of this invention.

Referring now to Fig. 2, it will be observed that cavities 14 are connected to central cavity 15 by slots 18. As is well known in the art, the gaps or openings comprising slots 18 have certain values of capacitance which are determining factors in the frequency of oscillation of these resonant cavities. Likewise, it is well known in the art that the portions of cavities 14 which comprise complete cylinders, except for the amounts removed to form slots 18, have relatively lumped values of self-inductance which also have a controlling effect on the operating frequency of these resonant cavities. To be sure, there are both self-inductance and capacitance which, in addition to these easily discernible lumped parameters, are distributed through such resonant cavities and are sometimes present in

the least obvious of places. However, relatively lumped values do exist in the areas described.

Dielectric blocks 19 are mechanically supported by a structure, which will be described hereinafter, so that they can be inserted into slots 18 or extracted therefrom. It is obvious that the presence of dielectric blocks 19 between the faces of slots 18 would markedly affect the value of capacitance existing across these slots especially if blocks 19 have a high value of dielectric constant. Likewise the presence or absence of metallic slugs 20 in the center of the inductive loop formed by cavity 14 has a marked effect upon the self-inductance of those loops. Accordingly, metallic slugs 20 are likewise supported by a structure, to be described herein-after, in such a manner that they can be inserted into or withdrawn from cavity 14.

Referring now again to Fig. 1, it will be seen that dielectric blocks 19 are connected at their upper ends to rods 21 and that metallic slugs 20 are connected at their upper ends to rods 22. Rods 21 and rods 22 are part of the means used to control the positions of these elements. In length rods 21 are shorter than rods 22. This difference in length is such that the ends of dielectric blocks 19 occur where the beginnings of metallic slugs 20 occur. Because of this construction it is obvious that when metallic slugs are fully within cavity 14, dielectric blocks are fully outside of slots 18, and vice versa. The upper ends of all rods 21 and all rods 22 are fastened into structure 23 which has substantially the shape of a large washer whose outer diameter is approximately as long as the outer diameter of the magnetron and whose inner diameter is approximately the same as that of inner cavity 15. The top ends of rods 21 and of rods 22, that is those ends which are not connected to dielectric blocks 19 or to metallic slugs 20 respectively, are fastened into structure 23 by any suitable means such as welding, brazing, or silver soldering. The four pairs of rods, each of which pair consists of a rod 21 and a rod 22, are free to move into and out of case 10 through four holes 24. Each of the four holes 24 is positioned approximately above a cavity 14 and is sufficiently larger than said cavity 14 so that each pair of rods consisting of a rod 21 and a rod 22 fit through holes 24 without touching case 10 at any point. Fastened above holes 24 with airtight junctions are four Sylphons 25. An end of each of these metallic bellows-like structures is fastened to case 10 in the position described above and the other ends are fastened to structure 23. In this way rods 21 and rods 22 are free to be pushed into or withdrawn from case 10 while at the same time a high vacuum can be and is preserved within case 10 and, of course, within Sylphons 25. Any suitable means can be used for moving structure 23. Such means could, for example, take the form of lever means or of screw means, and they could be designed in any of a number of conventional ways.

The foregoing portion of this application has disclosed the physical structure of this embodiment of this invention. The principles governing its operation will be set forth below.

Elements similar to metallic slugs 20 have been used in tunable magnetrons in prior art. They can be looked upon as single turn inductive loops which are short circuited and which can be coupled with the inductance of cavities 14 by inserting them within these cavities. It is

well known in the art that the presence of a short circuited single turn slug coupled to an inductance decreases the self-inductance thereof and that said self-inductance can be considered as changing its inductance value in the same way as the primary of a transformer which has its secondary connected to a low impedance load. As was explained above the presence of the dielectric blocks 19 has a well known effect upon the capacitance of these resonant cavities. Their use in producing this effect has advantages over the prior art use of metallic inserts. Metallic inserts, by lessening the air gap of slots 18, also increase the capacity of these slots. However they offer conductive current paths which are long enough with respect to certain wave-lengths to give rise to spurious resonances. The use of dielectric material, while it retains the ability to vary capacitance, avoids these long conductive current paths.

Since metallic slugs 20 and dielectric blocks 19 are arranged so that slugs 20 are withdrawn at the same time that dielectric blocks 19 are inserted, and vice versa, it follows that when the structure is moved so as to compress or extend Sylphons 25, the inductance and capacitance with either increase simultaneously or will decrease simultaneously, and accordingly the L-C product can increase rapidly or decrease rapidly.

Moreover the "Q" of the magnetron tends to be relatively constant over the tunable range of frequency when this arrangement is used, since, when losses due to the insertion of blocks 19 progressively increase and lower the "Q" of cavities 14, losses due to the withdrawal of metallic slugs 20 progressively decrease and raise the "Q." This same compensating action applies when the direction of adjustment is reversed. However this is not true to any comparable extent where the capacity-varying means are metallic inserts such as the means known to the prior art. Metallic inserts when placed in an electric field do not cause large losses and do not compensate for the withdrawal of inductance loading slugs.

Referring to Fig. 4, it will be seen that this improvement is readily adaptable to a vane type of magnetron. A conventional vane type magnetron is shown in Fig. 3 and the only difference between that magnetron and the improved one of Fig. 4 is that elements 27, in the improved type, consist of dielectric material whereas in Fig. 3 the corresponding elements 28 are metallic. In the vane type of magnetron the portions of the resonant cavities which open into the central cavity containing the cathode and which have the form of openings between adjacent vanes are capacitive areas corresponding to slots 18 of Fig. 2. The use of dielectric blocks in these spaces has the same effect of increasing the lumped capacity in this area as that effect already described above. Accordingly dielectric elements 27 in Fig. 4 are indicated with positions generally corresponding to the positions of dielectric blocks 19 of Figs. 1 and 2. Metallic slugs 20 of Figs. 3 and 4 situated in the inductive area of the cavities of this vane type magnetron are in all respects the same as metallic slugs 20 in Figs. 1 and 2 and perform the same function.

It will be seen that the magnetrons herein set forth are capable of being tuned over a wide range of frequency at the same time that they are less prone to spurious resonances and to wide variations in "Q" than are conventional tuned magnetrons.

It will be obvious to those skilled in the art

that no particular precise form of inserts or slugs is necessary and that no particular form of control mechanism, such as that shown in Fig. 1, need be employed for varying their positions within the cavities. Dielectric blocks having different values of dielectric constant might readily be employed for specific applications, and these blocks might be tapered or deformed in shape so that the rate of change of frequency for a given movement of the control elements would follow some desired pattern.

While there has been described what is at present considered to be the preferred embodiment of this invention it will be obvious to those skilled in the art that various changes and modifications may be made therein without departing from the scope of the invention, and accordingly I claim all such modifications that fall within the spirit and scope of the hereinafter appended claims.

The invention claimed is:

1. A magnetron comprising a cylindrical cathode, a plurality of cavity resonators concentrically disposed around said cathode and each having an open end facing said cathode, a case enclosing said cavity resonators, and an axially expandable Sylphon means connected to said case, said Sylphon means being disposed perpendicular to the axis of said cathode, frequency adjusting means including a plurality of inductance loading conductive elements, each centrally disposed in one of said cavity resonators, and a plurality of dielectric insert capacity-varying elements, each extending substantially across the open end of one of said cavity resonators, all of said inductance loading elements and all of said dielectric inserted elements being adjustably supported within said resonators of said magnetron by said Sylphon means, whereby the amounts that the inductance loading elements

and said dielectric insert elements are inserted into said resonators are simultaneously adjustable and whereby the frequency of oscillation may be adjusted over a range of frequencies and spurious resonances are minimized.

- 5 2. A tunable magnetron comprising a cathode, a plurality of cavity resonators concentrically disposed around said cathode and each having an open end facing said cathode, a case 10 enclosing said cavity resonators, frequency adjusting means including an inductance loading conductive element and a dielectric capacity-varying element, a flexible Sylphon means connected to said case and disposed perpendicular to 15 the axis of said cathode for adjustably supporting both said loading element and said dielectric insert element within one of said cavity resonators, said conductive element being centrally disposed in said one of said cavity resonators and 20 said dielectric element extending substantially across the open end of said one cavity resonator, whereby the amount that said inductance loading element and said dielectric element are inserted or withdrawn from said resonator is adjustable and whereby the frequency of oscillation of said cavity resonator may be adjusted over a range of frequencies and spurious resonances minimized.
